UNITED STATES PATENT OFFICE

MICHAEL HAWIE, OF GREENS FARMS, CONNECTICUT

HOSE SUPPORTER

Application filed April 16, 1931. Serial No. 530,629.

This invention relates to improvements in hose supporters, and more especially to novel means for connecting the ends of the wire loop which receives the button employed in connecting a stocking to the supporter.

Such loops are usually made of wire, and the ends of the same are joined to the loop of the strap support by means of a metal tube or binder. The ends of the button loop continuously pull out of the tube or binder, and various expedients have been employed to eliminate this disadvantage. Generally, a metal tie strap is secured to the opposite sides of the loop below the ends thereof, and this tie strap will prevent the ends from pulling apart, but it has a tendency to tear garments and to irritate the flesh of the user of the supporter.

One of the salient objects of the present invention is to provide a hose supporter employing the usual tube or binder for joining the ends of the loop to the loop of the supporter strap without the necessity of using any metal tie strap; the button loop ends and binder being so shaped and assembled that engaging shoulders of the same prevent the loop ends from being pulled apart.

In accordance with the present invention, opposite sides of the end portions of the loop are flattened at some distance from the extremities thereof, and after the binder or tube is attached, the binder is distorted to engage flat sides of the loop, and this provides engaging shoulders on the loop and binder which securely lock the ends of the loop against outward movement.

With the foregoing objects outlined and with other objects in view which will appear as the description proceeds, the invention consists in the novel features herein-after described in detail, illustrated in the accompanying drawings, and more particularly pointed out in the appended claim.

Referring to the drawings,

Fig. 1 is an elevation of a strap loop and a button loop in proper relation to be secured together by a binder, and showing the flattened end portions of the button loop.

Fig. 2 is a perspective view of the binder.

Fig. 3 is a view similar to Fig. 1, but showing the binder connecting the two loops.

Fig. 4 is a like view taken from the opposite side and with certain parts broken away.

Fig. 5 is a sectional view on the line 5—5 of Fig. 3.

In the drawings, 6 designates a button loop made of conventional cylindrical wire and 7 designates a conventional strap loop. Usually, such loops are connected by a binder 8 of the kind shown in Fig. 2, which binder is pressed into tubular form around the end portions of the wires which form the loops. However, as the ends of the button loop are liable to pull apart, various expedients have been employed to eliminate the difficulty, but all of such expedients are more or less objectionable. I have removed the disadvantage by employing the same parts and without resort to additional elements. Pursuant to my invention, the opposite sides of each end portion of the loop 6 are swaged or flattened, as shown at 9, and this provides abrupt shoulders 10 between the flattened portions and the cylindrical coaxial extremities 11 of the loop.

After the loops have been placed in proper relation, as shown in Fig. 1, the binder 8 is bent around the same to form a connecting tube, as shown in Figs. 2 to 5 inclusive, and then the end portions of the tube are depressed, as shown at 12, so that they come into engagement with the flattened faces 9 of the loop. This distorting of the tube forms shoulders 13 in the same at opposite sides of the cylindrical extremities 11 of the button loop, and these shoulders cooperate with the shoulders 10, so as to form an interlock which prevents the loop ends from being pulled apart.

From the foregoing it is believed that the construction and advantages of the invention may be readily understood by those skilled in the art, and it is apparent that changes may be made in the details disclosed, without departing from the spirit of the invention, as expressed in the claim.

What is claimed and desired to be secured by Letters Patent is:

A garment supporter or the like, comprising a button loop formed of substantially cylindrical wire and having coaxial end por-

15 tions, each of said end portions having a substantially cylindrical extremity and opposite flattened faces at its sides arranged adjacent to its said extremity, each end portion also having a shoulder between its flattened faces and its said extremity, said flattened faces forming cavities at opposite sides of said end portions, a strap loop, and a tubular metal binder joining said loops and having end portions aligned within said cavities and snugly engaging said flattened faces and said cylindrical extremities, the binder having shoulders interlocking with the shoulders of the button loop to prevent the ends of the button 20 loop from pulling apart.

In testimony whereof, I have signed this specification.

MICHAEL HAWIE.
